Application June 26, 1944, Serial No. 114,198

Term of patent 14 years

(Cl. D41—1)

To all whom it may concern:

Be it known that we, Robert J. Stoddard, William Niessen, and Charles Milnar, citizens of the United States, residing at St. Paul, in the county of Ramsey and State of Minnesota, have invented a new, original, and ornamental Design for a Truck for a Traveling Crane, of which the following is a specification, reference being had to the accompanying drawing, forming part thereof.

Fig. 1 is a top plan view of a truck for a traveling crane showing our new design;

Fig. 2 is a side elevational view;
Fig. 3 is a front elevational view; and
Fig. 4 is a rear elevational view.

The opposite side of the device is substantially the same as shown in Fig. 2.

We claim:

The ornamental design for a truck for a traveling crane, as shown and described.

ROBERT J. STODDARD.
WILLIAM NIESSEN.
